UNITED STATES PATENT OFFICE.

ALEXANDER WINTON, OF LAKEWOOD, OHIO.

VALVE STRUCTURE FOR INTERNAL-COMBUSTION MOTORS.

1,821,580.

Specification of Letters Patent. Patented Nov. 11, 1919.

Application filed December 20, 1915. Serial No. 67,877.

To all whom it may concern:

Be it known that I, ALEXANDER WINTON, citizen of the United States, residing at Lakewood, in the county of Cuyahoga and State of Ohio, have invented certain new and useful Improvements in Valve Structures for Internal-Combustion Motors, of which the following is a specification.

This invention relates generally to internal combustion motors and particularly to a multiple valve structure utilized for the intake and exhaust.

More specifically the invention relates to a multiple valve structure arranged preferably in the head of an internal combustion motor, for each of the intake and exhaust, both valves in each instance being used in conjunction with a single operating unit, whereby the two valves will open and close simultaneously.

The invention may be further briefly summarized as consisting in the construction and combination of parts hereinafter set forth in the following drawings, description and claims.

Referring to the drawings, Figure 1 is a view in side elevation of a portion of an engine showing the valve structure applied; Fig. 2 is a top plan view of the valve operating unit; and Fig. 3 is a sectional view through the valve mechanism, showing a portion of the cylinder head in section.

In the embodiment shown the device is applied to an engine comprising a cylinder 1 having a cylinder head 2, and a suitable cam shaft housing 3, receiving and supporting a cam shaft 4, adapted to be driven and operated from the engine shaft in a manner not shown or described. Suitable cams 5, one of which is shown in the drawings, operate the corresponding rocker levers 6, supported upon a suitable shaft or pin 7. Each of these levers is provided with a friction roller 8, engaging one of the cams 5, and a roller 9 at the opposite end for engagement with the corresponding valve mechanism, which will now be described in detail.

The multiple valve feature disclosed in this application may be utilized with either or both of the intake and the exhaust, and in either instance the mechanism is the same so that a description of one will suffice for both, the object being to provide the greatest

possible valve opening without interfering with the remaining structure of the cylinder head.

Each of the cylinder heads 2 is provided with a suitable chamber 10 arranged above the exhaust and the intake valves, and each of these chambers communicates by suitable openings 11 with the cylinder, there being a valve seat 12 about each of the openings 11. In the central alignment with each of the openings 11 is a valve guide 13 adapted to receive the usual valve stem 14, preferably provided at its lower end with a mushroom valve 15 adapted to coöperate with the corresponding valve seat 12. As before intimated there are two of these complete valves and seats for each, the intake and the exhaust. Each of the valve stems 14 extends out through its guide 13 and is provided at its upper end with an annular recess 16, receiving the halves 17 of a split ring, adapted to engage in a recess 18, formed in the thrust washer 19. A spring 20 is arranged between this thrust washer and the cylinder head for holding the valve seated.

The operating unit for each pair of valves, either the intake or the exhaust, comprises a supporting or base plate 21 adapted to extend between the two valves and to be held in place by bolts or cap screws entering the openings 22. Extending upward from this supporting plate 21 is a tubular guide 23, having an opening 24 on one side and in the bottom for a purpose to be described. This tubular guide 23 receives a hollow guiding shank 25, forming a part of an operating plate 26, which has oppositely disposed portions extending out over the two valve stems. Mounted in this plate above each of the valve stems is a tappet screw 27 threaded through the plate and held in place by a suitable check nut 28. Each of these screws engages a valve stem as stated, and they may be provided with suitable finger pieces 29 for adjusting them. Arranged inside of the hollow guide 25 and the tubular guide 23 is a coiled spring 30, which normally tends to move the plate 26 and its guide 25 upward into engagement with the roller 9 of the corresponding rocker lever 6. In order to prevent the operating plate or member from rotating so that its tappet screws are out of proper relationship with respect to the valve stems, the plate 26 is

provided with a suitable opening for receiving a pin 31, mounted in and extending upward from the supporting plate 21.

It will be seen from the foregoing construction that when the valve operating end of the rocker lever is in its uppermost position, as shown, the spring 30 will cause the operating plate 26 to press against the under side of the roller 9 and take up any lost motion between the plate and the corresponding cam 5. The tappet screws may then be adjusted properly with respect to the valve stems. In operation the rocker levers, as they are rocked, engage the plates 26 and move the valves controlled by them downward, causing their simultaneous operation.

Some of the principal points of invention are: the use of a plurality of valves on either 20 the intake or the exhaust, or both; the operation of any one set by a single operating unit; the taking up of any lost motion between the valve operating unit and the cam; and other details of construction set forth 25 in the specifications and claims.

Having described my invention, I claim:—

1. In an internal combustion motor, a cylinder, a cylinder head having a plurality 20 of valve openings and seats of one type, either exhaust or intake, valves engaging said seats, valve stems carried by said valves and extending to the outside of the cylinder head,

and an operating unit engaging said valve stems for simultaneously operating said 35 valves, and comprising a base, a tubular guide, a hollow member engaging in said guide, a valve operating plate carried by the hollow member, a spring within the hollow member intended to force the plate 40 away from the valve stems, and means independent of said valve stems for preventing rotation of the operating plate.

2. In an internal combustion motor, a cylinder, a cylinder head having a plurality 45 of valve openings and seats of one type, either exhaust or intake, valves engaging said seats, valve stems carried by said valves and extending to the outside of the cylinder head, and an operating unit for simultaneously 50 operating said valves, and comprising a base, a tubular guide, a hollow member engaging in said guide, a valve operating plate carried by the hollow member, a spring within the hollow member intended to force the plate away from the valve stem, and means for preventing rotation of the operating 55 plate, comprising a rod mounted in the base and extending through an opening in the operating plate.

In testimony whereof I affix my signature in presence of two witnesses.

ALEXANDER WINTON.
